his Attorney.

UNITED STATES PATENT OFFICE

HENRY KOCOUREK, OF CHICAGO, ILLINOIS

ARC LAMP

Application filed April 22, 1929. Serial No. 357,046.

The purpose of this invention is to provide an improved and simplified construction of an arc light lamp, a principal purpose being to reduce the number of parts, and thereby the cost of construction and assembling, and to so form the several parts that they may be securely assembled without screws or bolts, except the binding screws for the energizing circuit wires. It consists 10 in the elements and features of construction shown and described as indicated in the claims.

In the drawings:—

Figure 1 is a vertical axial section of an arc light lamp embodying this invention.

Figure 2 is a dissected view showing the several parts in side elevation separated axially except as to the intermediate portion of the casing shown in section in true position and a reflector which is shown turned 90° from assembled position.

Figure 3 is a detail section at the plane indicated by the line 3—3 on Figure 2, treating the cap member as in true position with 25 respect to the core.

Figure 4 is a section in the same axial plane as Figure 1 showing the core and the energizing circuit wire wound as a resistance coil thereon and the carbon sockets and 30 circuit terminals which are connected by the coil.

Figure 5 is a front elevation of a collar which forms the front end element of the casing and shields for the ventilating apertures of the reflector.

Figure 6 is a fragmentary detail in the nature of a side elevation of the core, looking in the direction of the arrow 6 on Figure 4.

Figure 7 is a fragmentary view taken substantially as a section at line, 2—2, on Figure 1.

Figure 8 is a section radially of the core member in a plane 45 degrees around from 45 that of Figure 4.

The construction shown in the drawings comprises an insulating core member which may be of porcelain, and a sheet metal casting enclosing it, and a reflector mounted at 50 the forward end of the core, the core having

at the rear end circuit terminals for engagement by a circuit plug, and having sockets for carbons between whose forward ends the illuminating arc is formed when the lamp is energized.

The core is formed with a main portion intermediate its ends, reduced in diameter, this intermediate portion being spirally grooved for seating the inleading energizing circuit wire which by virtue of its conductive character and length in its spiral windings about the core affords the resistance necessary for proper operation of the lamp.

Referring more particularly to the drawings, the insulating core member, A, has the intermediate portion of its length indicated at A¹ reduced in diameter relatively to the rear end portion, A², and the forward end portion, A³, which are of equal diameter. The core has toward the rear end a diametric bore, 26, and toward the forward end a similar bore, 27, said bores being within the limits of the intermediate reduced portion of the core. The core is recessed at the rear end, at 20, 20, for holding circuit terminals, 21 and 22, which extend across the rear end bore, 26, and are insulated from each other by the intervening substance of the core, and are apertured and threaded at their exposure in the bore, 26, for binding screws, 23 and 24. At the forward end the core is recessed at 30 for carbon holding sockets, 31 and 32, which are insulated from each other by a mica spacer, 35; these sockets extend inward across the forward bore, 27, 85 and are bored and threaded at their exposure in said bore for binding screws 33 and 34 respectively. The core is radially rifted at one side as seen at 28, said rift, 28, extending between and connecting the bores, 26 and 27, at one side of the axis of the core. The circuit wire constituting the resistance winding is indicated at 50, having one end secured by the binding screw, 23, to the circuit terminal, 21, and the other end secured by the binding screw, 33, to the carbon holding socket, 31, the opposite end portions of the wire being led in from the spirally wound portion to the binding screws, 23 and 33 respectively, through the diametric bores, 26

and 27 respectively. The circuit comprising the arc which will be formed between the ends of the carbons is completed by wire, 40, which is entered through the rift, 28, for securement by binding screws, 24 and 34 respectively, to the circuit terminals, 22, and the carbon socket, 32.

As shown, the mica spacer, 35, extends beyond the metallic carbon holding sockets, 31 and 32, at both ends of the latter, and also at the sides (as seen in Figure 7), the extension being sufficient to prevent the current from jumping across from one of said sockets to the other around the edge of the mica spacer, 35.

For encasing the core and the circuit elements thereon and therein there is provided a sheet metal casing consisting of a rear end cap, B, a forward end collar, B¹, and a perforated cylindrical body member, B², said intermediate body member being dimensioned for being passed onto the core over the full diameter end portions for encompassing the intermediate reduced portion of the core with spacing therefrom by the amount of the reduction of diameter of said intermediate portion, so that there is formed a clear annular space around the resistance windings to provide for ventilation of the resistance winding as well as to prevent the liability to short-circuiting by contact with the casings. And for thus positioning said intermediate casing member, B², it is interiorly dimensioned for fitting closely the full diameter end portions, A² and A³, of the core.

The rear end cap, B, is formed as by stamping or spinning to fit the form of the rear end of the core and has a central aperture, 60, registering with a recess, a, in which the circuit terminals, 21 and 22, protrude. At its periphery the cap is formed reflexed inwardly forming an annular shoulder, as seen at 61, and the inturned flange is folded at right angles to its inturned direction, that is, so as to extend longitudinally of the core parallel to the axis and the core has a circumferentially extending rabbet indicated at 67 which accommodates the entire cylindrically inturned flange which, however, is divided into segments, 63 and 64, of which alternate segments, 63, are folded inwardly, that is, back into the plane of the inturned flange, the core being formed with a series of notches or rabbets, 66, alternating with projections, 65, for accommodating the infolding of said alternate segments. The cap, B¹, is thus securely locked to the rear end of the core with the alternate segments 64 which were not folded into the rabbet, 66, as mentioned, constituting an interrupted cylindrical flange whose diameter is that of the unreduced end portion of the core, so that the cylindrical case member, B², is adapted to telescope with said interrupted flange

when it is slipped over the core from the forward end of the latter and thrust rearward into such telescoping engagement with the rear end cap and stopped against the annular shoulder, 61.

The unreduced forward end portion, A³, of the core is peripherally grooved as seen at 75 and 76, and provided with notches, 77, extending across both grooves and constituting entrances to both grooves. The front end collar, B¹, is frusto-conical in form, that is, flared from one end to the other, the smaller end having an inturned marginal flange which is interrupted by notches, 81, leaving segments, 80, between the notches, 81, for becoming engaged with said grooves. The segments, 80, are slightly oblique to the axis, while the groove, 75, lies in planes perpendicular to the axis so that when the segments, 80, are introduced through the notches, 81, the turning of the collar causes the oblique segments to act as cams, and the collar may be said to be screwed back against the forward end of the cylindrical casing member, B², forcing the latter back snugly against the shoulder, 61, of the rear end cap.

The reflector, D, is formed at its rear open end, which is to be engaged with the core, somewhat similar to the collar B¹. Its narrow central flange is subdivided into alternate segments, 83 and 84, the segments 83 constituting notches and the segments 84 comprising inwardly extending lugs dimensioned to enter the notches 77 of the core and then to engage the groove 76 when the reflector is rotated. These lugs 84 are slightly oblique so as to be sprung as they enter the groove and thus secure a frictional hold in the groove 76 to retain the reflector in position.

The reflector is formed with ventilating apertures, 86, in circular arrangement quite closely proximate to its engagement with the core; and the collar, B¹, in addition to the function of binding the cylindrical casing member, B², between said collar and the rear cap, performs the additional function of screening the ventilating apertures of the reflector both to prevent light being emitted through the apertures in undesired direction, and also to prevent or reduce the liability of dust and water being dashed or blown into contact with the carbons from the rear.

It is desirable to have the reflector, D, removable so that in washing or polishing it the carbons and adjacent parts will not get wet and will not interfere with free access to the interior surface of the reflector. It may also be more convenient to pack the lamp for shipment if the reflector is removable, so that it can be telescoped over other parts of the structure.

The cylindrical shell or casing, B², is conveniently made with a lapped joint at 90, secured by rivets 91, the metal being offset in

wardly at one end of the piece to form this joint and thus forming an inwardly projecting rib or protrusion in the shell B^2 . This rib interlocks with a groove, 92, formed in the core member, A, and thus holds the core against rotation in the shell. Preferably the blank from which the shell B^2 is made includes lugs 94 which depend from the cylindrical shell at opposite sides of the joint 90, and are perforated to receive a clamping screw 95 by which the lamp body is secured to the base 96.

I claim:

1. In a structure for the purpose indicated in combination with an insulating core body, an enclosing sheath comprising a cylindrical member dimensioned for being fast onto the core for encompassing an intermediate portion of its length; a rear end cap forwardly terminated by a cylindrical flange offset inwardly from the outer circumference of the cap, forming an annular shoulder encompassing said cylindrical flange, the latter being divided into segments of which alternate segments are folded inward for engaging the end cap with the core against endwise displacement, the core being recessed to accommodate the infolded segments and also having a circumferentially extending rabbet in which the cylindrical flange is seated; whereby the cylindrical case member, dimensioned as stated, is adapted to telescope over said cylindrical flange and be stopped against said encompassing shoulder.

2. In an arc lamp in combination with an insulating core body, an enclosing sheath comprising a cylindrical member dimensioned for being passed over the core body for encompassing an intermediate portion of its length, the core having a circumferentially positioned groove located a short distance back from its forward end beyond the forward end of the cylindrical case member, with notches entering said groove from the forward end of the core, and a front locking collar having lugs dimensioned for entering through the notches into the groove for engaging the collar with the core, said groove being positioned for causing the collar engaged therewith to stop the cylindrical sheath member and be stopped against the forward end thereof.

3. An arc lamp comprising in combination with a core consisting wholly of insulating material, a casing consisting of a rear end cap covering and bearing upon the rear end of the insulating core; a front end collar through which the core extends and is exposed forwardly, and an intermediate cylindrical member bound endwise between the cap and the collar, the cap being engaged with the insulating core at the rear end of the latter against relative longitudinal movement, and the collar being disengageably engaged with the core insulating toward the

forward end of the core; whereby the insulating core is positively stopped longitudinally between said rear end cap and front end collar.

4. In the construction defined in claim 2, the lugs of the collar being slightly oblique to the groove to act as cams against a wall of the groove for wedging the collar against the end of the cylindrical sheath member.

5. A construction for the purpose indicated comprising in combination with a core of insulating material, a casing consisting of a rear end cap covering the core; a front end collar exposing the core, and an intermediate cylindrical member bound endwise between the cap and the collar, the cap being engaged with the core at the rear end of the latter, and the collar being disengageably engaged with the core toward the forward end of the core, and a reflector disengageably engaged with the core at the forward end portion thereof which is within the collar forwardly of the engagement of the latter with the core.

6. A construction for the purpose indicated comprising in combination with a core of insulating material, a casing consisting of a rear end cap bearing upon and covering the rear end of the core, a front end collar bearing upon and exposing the forward end of the core, and an intermediate cylindrical member bound endwise between the cap and the collar, the cap being engaged with the core at the rear end of the latter, and the collar being disengageably engaged with the core toward the forward end of the core, whereby the core is positively stopped longitudinally between the rear end cap and the forward end collar, the core being reduced in diameter over the main part of its length intermediate the engagement therewith of the rear end cap and the front end collar, and spirally grooved at said reduced part for seating a resistance winding, and having toward the limits of said reduced portion diametrically extending apertures; plug-engaging circuit terminals mounted in the core at the rear end and accessible through the rear end cap for engaging a plug, said terminals being spaced apart laterally, extending across the rear diametric aperture and bored and threaded in alignment therewith for binding screws.

7. A construction for the purpose indicated comprising a core of insulating material reduced in diameter for the main portion of its length intermediate its ends, and formed at said reduced portion for seating a resistance winding; a casing enclosing the reduced part of the core dimensioned interiorly for being passed over the unreduced end portions and centralized thereby with respect to the reduced portion, whereby there is enclosed an annular space around the resistance windings seated on the reduced portion, the core being suitably recessed at the front end

for accommodating carbon sockets side by side insulated from each other, and at the rear end for seating circuit terminals side by side insulated from each other, for engagement by a circuit plug and suitably apertured for leading the opposite ends of a resistance winding respectively from the surface of the reduced portion to the carbon sockets and to the circuit terminals at one side, and for accommodating a circuit completing wire connecting the carbon socket and the circuit terminal at the other side.

8. A construction for the purpose indicated comprising a core of insulating material having proximate the rear and front ends respectively diametric bores in the same diametric plane, and being reduced in diameter at an intermediate portion of its length including the position of said bores, and having a radial rift at said intermediate reduced portion connecting said bores at one side of the access, said reduced portion being arranged for winding thereon resistance coil; the core having at the front end a centrally located recess extending in to the front end bore; carbon sockets lodged insulated from each other in said recess and extending alongside each other in said front end bore, and having their end portions which are exposed in said bore, bored and threaded for binding screws; circuit terminals for plug connection mounted insulatedly in the core at the rear end thereof extending across the rear end diametric bore provided with binding screws at their respective intersections with said bore, and protruding rearwardly for engagement by a plug; a resistance coil secured at one end to one of said circuit terminals and at the other end to the carbon socket at the same side, and a circuit completing wire lodged in the radial rift and secured at its ends respectively by binding screws to the other circuit terminal and to the other carbon socket.

9. A construction for the purpose indicated comprising in combination with a core of insulating material, said core being reduced in diameter for the main portion of its length intermediate its ends, and having toward the limits respectively of said reduced portion diametrically extending apertures; circuit terminals mounted in the core at the rear end and protruding for engagement of a plug, said terminals being spaced apart laterally and extending across the rear diametric aperture and bored and threaded in alignment therewith for binding screws, the core being recessed at its forward end, and carbon-holding sockets inserted in said recess, said sockets being insulated from each other and having their rear ends extending across the forward diametric aperture and bored and threaded in alignment therewith for binding screws, a resistance coil wound on the reduced portion of the core, having one

end extending in the rear diametric aperture and secured by a binding screw to one of the circuit terminals, the other end extending in the corresponding portion of the front diametric aperture and secured by binding screw to the corresponding carbon socket, the core having at the side opposite the binding screw connections mentioned of the resistance winding a radial rift connecting the portions of the diametric apertures at said opposite side, and secured at its opposite ends respectively by binding screws to the circuit terminal and the carbon socket respectively at that side.
